METHOD OF MAKING GOODYEAR-WELT SHOES

Albert Kamborian, Newton, Mass., assignor to
Jacob S. Kamborian, West Newton, Mass.

Application October 8, 1949, Serial No. 120,279

1 Claim. (Cl. 12—145)

1 This invention relates to the making of footwear and more especially to a novel method of making Goodyear welt shoes.

In a Goodyear welt shoe, the lasting margin of the upper and the inner edge portion of the welt are united by the inseam stitches to the sewing rib of the insole. Prior to the formation of the inseam, the upper is subjected to lasting stress (applied to the lasting margin) to draw the upper snugly about the last. As this stress is applied, the margin is secured to the insole, either by the use of temporary tacks or by staples which are inserted approximately at the point where stress is being applied.

The lasting operation, whether carried out by hand or by machine (at least, until comparatively recently) customarily included the steps of pulling over, side lasting, heel lasting and toe lasting.

Pulling over involves the proper positioning of the upper on the last and the initial steps involved in stressing the toe portion of the upper. The toe portion of the upper, after being stressed, is held in position by means of partially-driven temporary tacks—usually one at the tip of the toe, two at each side of the shoe at the tip line and one on each side just back of the tip line. In the side-lasting operation the upper (including the lining) from heel breast to tip line, is drawn tightly down to the wood of the last at each side of the last. In accordance with older practice, it was held in position by temporary tacks but following more recent practice, the lasted-in margin is permanently fastened to the insole rib by a series of wire staples. Following the side lasting, the heel end of the upper is lasted in, usually by means of a machine having wipers which wipe the upper, counter and lining in over the bottom of the last to which they are permanently secured by tacks. The toe lasting is accomplished, as a machine operation, by the use of wipers which wipe the toe portion of the lasting margin, including the lining margin and the toe box, down snugly against the outer surface of the insole rib, the pulling-over tacks having previously been removed and the wiped-in material being held in place by a toe wire and anchor tacks—at least until the shoe is ready for the inseaming operation.

The usual staple side-lasting machine operates step-by-step—gripping and stressing the margin and driving a staple at one point and then repeating the process at a point spaced along the margin from the first point. The machine thus follows the old hand-lasting method insofar as its intermittent action is concerned, or the op-

2 eration of the so-called "Nigger head machine" which was and still is used extensively for side lasting. At each point where a staple is driven (or a tack, if tacks are employed), the full lasting tension is preserved, but portions of the margin (intervening between the staples or tacks) which are not directly secured to the insole tend to relax and to bulge out, so that the lower portion of the upper of the completed shoe exhibits a wavey or undulant appearance which is not consistent with the demands of fine shoe making. Moreover, as the staples are driven close to the edge of the rib (to avoid needle breakage when the inseam is formed) the lasting margin tends to bridge the angle between the insole feather and rib. This interferes with the inseaming operation and results in a bad edge.

The present invention has for its object the provision of a novel method of making Goodyear welt shoes whereby the above disadvantages, inherent in the customary prior practices using staples or tacks, are avoided. A further object is to provide a novel method of making Goodyear welt shoes such that the margin of the upper is permanently secured to the insole at every point along the periphery of the insole rib. A further object is to provide a method of making Goodyear welt shoes whereby the margin of the upper is more firmly secured to the insole than by previous methods. A further object is to provide a method of making Goodyear welt shoes whereby the lasting margin is forced substantially to the apex of the angle between the insole feather and rib and is permanently secured to the rib and feather. A further object is to provide a novel method of making Goodyear welt shoes wherein the lasting stress to which the upper is subjected is preserved without possibility of relaxation until the inseam stitches are formed and without the use of metallic fasteners. A further object is to provide a novel method of making Goodyear welt shoes wherein the lasting margin of the upper is united to the insole solely by means of adhesive prior to the formation of the inseam. Other and further objects and advantages of the invention will be pointed out in the following more detailed description and by reference to the accompanying drawings wherein

Fig. 1 is a fragmentary, diagrammatic, transverse section, to large scale, illustrative of a conventional Goodyear insole;

Fig. 2 is a view similar to Fig. 1 showing the insole prepared for lasting in accordance with the present invention;

Fig. 3 is a fragmentary, diagrammatic, trans-

verse section, to large scale, showing the insole of Fig. 2 assembled with a shoe upper on a last in readiness for the lasting operation;

Fig. 4 is a view similar to Fig. 3 but showing parts of a lasting machine of the continuous type in performing the lasting operation;

Fig. 5 is a fragmentary perspective view, to smaller scale, illustrating the progress of the lasting operation as performed by mechanism slightly different from that shown in Fig. 4;

Fig. 6 is a view similar to Fig. 4 but omitting the lasting machine parts and diagrammatically showing the appearance of the shoe after completion of the lasting and inseaming operations;

Fig. 7 is a view similar to Fig. 3 but illustrating a modified procedure;

Fig. 8 is a view generally similar to Fig. 4 but illustrating a lasting machine of a slightly modified type;

Fig. 9 is a diametrical section, to larger scale, through the inner roll, showing details of the hold-down foot; and

Fig. 10 is a fragmentary vertical section through the abutment and hold-down of Fig. 3.

Referring to the drawings, the numeral 1 designates an insole of conventional Goodyear welt type, usually comprising a body portion made from leather, or a substitute for leather, shaped to provide the sewing rib 2 and the marginal feather 3 and usually having a reinforce 4 of canvas or the like secured to an under surface of the body portion of the insole and forming an inner ply of the sewing rib.

In accordance with the present invention, the outer surface of the sewing rib and the under surface of the feather are coated (Fig. 2) with a layer 5 of adhesive. This coating may be applied either before or after assembly of the insole and last, depending upon the kind of adhesive used and the dictates of convenience. According to a preferred embodiment of the invention, this layer of adhesive will be of a normally non-tacky, thermoplastic material, for example, one of the synthetic resins. However, in accordance with another embodiment of the invention, this layer may be a pressure-type adhesive which is normally non-tacky and which does not have substantial tendency to stick to other materials but which has a strong adhesive affinity for surfaces coated with similar material, even at ordinary temperatures, when subjected to pressure. Preparatory to lasting, the inner surface of the lasting allowance or margin of the upper is likewise coated with adhesive. If the upper includes a lining, the constituent parts of the upper, at the marginal portion, will be adhesively or otherwise bonded together.

Having coated the sewing rib and the feather with this layer 5 of adhesive, the insole is then assembled on the last with an upper U having the lasting allowance or margin M, as shown in Fig. 3. The shoe is now lasted either by the use of hand actuated appliances or by any appropriate power driven mechanism in such a way that the point of application of lasting stress progresses without interruption along the edge of the last. This is conveniently carried out by means of mechanism comprising rolls 6 and 7 (Fig. 4) fixed to shafts 8 and 9, respectively, one, at least, of the rolls being positively driven so as to exert a forward feeding action upon the work. Desirably the roll 7 has a rigid downward axial extension 7^a which forms an abutment for the sewing rib and contacts the bottom of the insole and constitutes a hold-down for the work. Prefer-

ably the extension 7^a is capable of axial movement and is urged downwardly by means of a spring S, its downward movement being limited by a stop 7^b. In presenting the work to the machine the operator engages the bottom of the insole with the lower end of the part 7^a and exerts upward pressure, thus compressing the spring S until the marginal material M is properly engaged between the rolls 6 and 7. As shown in Figs. 4 and 8 the margin M is gripped near its free edge only, the roll 7 or the abutment 16 being so spaced above the insole that the sewing rib is not gripped between the parts which grip the margin M. If desired the holdown 7^a may be capable of free rotation so as to form a roller abutment for engagement with the inner surface of the sewing rib. Other forms of work hold-down may be substituted. In one desirable arrangement (Fig. 5) the axes of the shafts 8 and 9 are inclined relatively to the bottom of the insole, such inclination being either an actual inclination of the roll axes to the vertical or relative, resulting from the inclination of the bottom of the shoe during the lasting operation. If the cement coating 5 be of a thermoplastic type such as to require that it be heated to make it tacky, provision may be made for supplying heat, for example, by means of a jet nozzle 10 (Fig. 4) from which a jet of heated or burning gas may issue so that the flame is directed upon the adhesive immediately before the adhesive coated material passes between the rolls, or the hot gas may be so directed that it will contact the roll 6 and thus heat the latter sufficiently to make the adhesive coating sticky. The roll 7 with its extension 7^a constitutes an anti-friction abutment (considering the roll 6 as the driven roll) for the inner side of the sewing rib so as to support the latter during the lasting operation and also acts as a hold-down to resist upward movement of the last. Preferably, both rolls are of a hard, rigid material and one or both of the rolls is mounted for bodily movement toward the other with provision for urging it, for example, resiliently, toward the other during the lasting operation so as to grip the upper margin and to press the latter against the coated surface of the sewing rib. Usually the machine will have an edge gage which engages the outer surface of the upper near the plane of the last bottom so as to assist the operator in presenting the work to the lasting machine. Some kind of wiper device is employed, for example a horizontal, reciprocating blade 11 (Fig. 4) or as illustrated in Fig. 5, a rotary helical wiper element 12, carried by the rotating shaft 13, to assist in working the marginal material inwardly and to press it firmly onto the feather of the insole.

The operation of continuous lasting in this manner proceeds uninterruptedly along that portion of the periphery of the shoe bottom at which lasting is to be done. It may continue around the toe but is usually limited to the shank and forepart portions.

After the upper has been lasted, as above described, whereby the lasting allowance is firmly secured to the sewing rib by adhesive means only and without the employment of independent fasteners, metallic or otherwise, the welt W may then be secured by the stitches 14 (Fig. 6) to the sewing rib in accordance with the customary practice, and without any danger that the needle of the sewing machine will be deflected or broken by contact with metallic fasteners of any sort.

When an adhesive of the normally non-tacky,

pressure type is used, it is especially desirable, as illustrated in Fig. 7, not only to coat the outer surface of the sewing rib with the adhesive 5, but, as above suggested, to coat the inner surface of the lasting allowance M with a similar adhesive 15, as shown in Fig. 7. The shoe is then lasted, as above described, except that it is not necessary to use heat during the lasting operation—the mere pressure of the two adhesive layers 5 and 15 against each other serving firmly to unite them.

While it is usually desirable that the adhesive coating 5 cover the feather 3 as well as the sewing rib, it is within the purview of the invention to omit the adhesive from the feather, which may be desirable at times to facilitate the in-working of the margin into lasted position.

While, as above suggested, the operation is conveniently carried out by a machine having opposed work-contacting rolls, it is possible to use other combinations of work gripping elements, for instance, such as shown in Fig. 8. In this arrangement, the outer roll 6 is such as above described, but the inner roll is replaced by a stationary, rigid abutment member 16 which supports the sewing rib. Associated with the abutment 16 is a hold-down device, preferably capable of vertical movement and urged downwardly by a spring S' (Fig. 10). This hold-down has a toe portion 17 which reaches down into the channel of the insole to form a hold-down device and which is furnished with the smoothly polished surface 18 opposed to the roll and designed to engage the inner surface of the sewing rib. The roll 6 is the driven element, acting to feed the work along and also to exert the up-drafting stress, the work sliding freely along the polished surface 18 of the abutment 16 which cooperates with the roll 6 to provide the desired grip for up-drafting the upper and which, at the same time, furnishes support for the sewing rib in opposition to the pressure exerted by the roll 6 in forcing the lasting allowance M into adhesive contact with the coated surface of the sewing rib.

While wiper devices such as 11 or 13 have been described as useful in the performance of the operation, it is possible for a skilled operator to last shoes merely by the use of the rolls 6 or 7, or their equivalent, without the assistance of any 50 wiper device.

In describing the improved method hereinabove, a certain sequence of steps has been suggested for convenience, but without intent to

limit the invention to that particular sequence, and the claims are likewise to be understood, in respect to the specific order of steps recited, as merely suggestive and not restrictive, and it is to be understood that the method is broadly inclusive of any and all procedures falling within the scope of the appended claim.

I claim:

The method of making shoes of the Goodyear-welt type wherein the lasting allowance of an upper, assembled with an insole upon a last, overlies the feather of the insole and, prior to attachment of the welt to the sewing rib of the insole, is secured to the rib by adhesive only, the outer face of the sewing rib of the insole having previously been coated with a normally non-tacky thermoplastic adhesive and the lasting allowance of the upper being of a width exceeding the combined widths of the feather and rib of the insole, said method comprising as steps supporting the shoe against a fixed abutment, a portion of which engages the insole at the base of the rib at the inner side of the latter and another portion of which engages the inner surface of the lasting allowance at the free margin of the latter, directing a jet of hot fluid against the adhesive coating, applying a positive updrafting stress to the free marginal portion only of the lasting allowance while the shoe is being restrained by said abutment against upward movement and, without ceasing to apply the updrafting stress, causing the point of application of said stress to progress continuously and uninterruptedly about the periphery of the insole, and, as the point of application of updrafting stress progresses, applying inwardly directed force to the stressed portion of the lasting allowance for working the latter inwardly over the feather of the insole and for pressing it against the adhesively coated surfaces of the feather and rib thereby to unite the lasting allowance to the insole.

ALBERT KAMBORIAN.
